UNITED STATES PATENT OFFICE.

AUGUST J. KLONECK, OF NEW YORK, N. Y.

SPEEDOMETER.

1,205,357.

Specification of Letters Patent.

Patented Nov. 21, 1916.

Application filed October 25, 1915. Serial No. 57,743.

To all whom it may concern:

Be it known that I, AUGUST J. KLONECK, a citizen of Germany, and a resident of New York, in the county and State of New York, 5 have invented certain new and useful Improvements in Speedometers, of which the following is a specification.

This invention relates to improvements in speedometers and has for its object to provide a speedometer with a fan for the indication of varying speeds.

Another object of the invention is to provide a speedometer with a rotating propeller and means whereby an air current, caused 15 by said rotating propeller is utilized to indicate the speed thereof.

Still another object of the invention is to provide the speedometer with a funnel or jacket, whereby an air current, produced by 20 said propeller may circulate and continuously be used.

With these and other objects in view, I have invented the device illustrated in the accompanying drawings in which:

25 The figure is a sectional elevation view of my improved speedometer.

In the drawing, 1 indicates a casing, housing a rotatable mounted propeller or fan 2. The latter is rigidly secured to the 30 driving shaft 3, which may in any suitable manner be connected to the device, whose speed is to be measured. Another propeller or fan 4 is arranged above the first named propeller 2, without any mechanical connection between them however. Said fan 4, 35 would rotate proportional to an air current produced by the propeller 2. The rotation of said fan 4, however is retarded by a convenient spring 5, permitting a rotation of

40 the fan 4 of few degrees only. A scale may be engraved on a convenient part of fan 4, which permits a direct reading of the propeller speed or the driving device. Through a funnel 7 formed by a jacket of the speedometer the air current produced by propeller 2 45 may circulate, thus preventing dust or other impurities to enter the speed indicator.

The speedometer may further be provided with a revolution counter of any form, the 50 construction of which is not essential for the present invention. I have shown a counter 8, which is operated by a treaded portion 9, on the circumference of propeller 2.

Having fully described my invention, that

which I claim as new and desire to secure by 55 Letters Patent is:

1. In a speedometer, an outer casing, an inner casing positioned at a side thereof and a mechanically driven fan and an air driven fan located in said central casing. 60

2. In a speedometer, an outer casing, an inner casing positioned at a side thereof and a mechanically driven fan and an air driven fan located in said central casing, said two casings forming a passage for air currents 65 therebetween.

3. In a speedometer, an outer casing, an inner casing positioned at a side thereof and a mechanically driven fan and an air driven fan located in said central casing, said two 70 casings forming a passage for air currents therebetween, said outer casing being entirely closed.

4. In a speedometer, an outer casing, an inner casing positioned at a side thereof and a mechanically driven fan and an air driven fan located in said central casing, said two casings forming a passage for air currents 75 therebetween, said outer casing being entirely closed and a revolution counter on 80 said outer casing and means within the casing for operating the same.

5. In a speedometer, an outer casing, an inner casing positioned at a side thereof and a mechanically driven fan and an air driven 85 fan located in said central casing, said two casings forming a passage for air currents therebetween, said outer casing being entirely closed and a revolution counter on 90 said outer casing and means within the casing for operating the same, said means consisting of a gear on said mechanically driven fan.

6. In a speedometer, an outer casing, an inner casing positioned at a side thereof and a mechanically driven fan and an air driven 95 fan located in said central casing, said two casings forming a passage for air currents therebetween, said outer casing being entirely closed, said air driven fan having an 100 indicator scale on the periphery thereof.

7. In a speedometer, a fan having a speed indicator thereon, said indicator consisting of a scale on the periphery of said fan, means whereby said fan may be operated by an air 105 current, said fan being spring controlled, said means consisting of a mechanically driven fan, a casing in which said fans are

mounted one above the other, a housing for said casing, a passage between said casing and housing whereby a continuous circulation of air contained in the housing is provided, in combination with a revolution counter, said last indicator being directly operated by said second fan.

8. A speedometer consisting of an air driven spring controlled rotary fan and a mechanically driven fan, said first fan carrying a speed indicator on the periphery thereof, said last fan being provided with means for operating a revolution counter.

9. In a speedometer, an outer casing having top, bottom and side walls, an inner casing located eccentrically of said top and bottom walls, a mechanically driven fan and an air driven fan in said inner casing.

10. In a speedometer, an outer casing having top, bottom and side walls, an inner casing located eccentrically of said top and bottom walls, a mechanically driven fan and an air driven fan in said inner casing and a spring for controlling said air driven fan.

25 11. In a speedometer, an outer casing having top, bottom and side walls, an inner casing located eccentrically of said top and bottom walls, a mechanically driven fan and an air driven fan in said inner casing and a spring for controlling said air driven fan, said two casings forming a passage for air currents therebetween.

30 12. In a speedometer, an outer casing having top, bottom and side walls, an inner casing located eccentrically of said top and bot-

tom walls, a mechanically driven fan and an air driven fan in said inner casing and a spring for controlling said air driven fan, said two casings forming a passage for air currents therebetween and a revolution indicator mounted in the outer casing.

13. In a speedometer, an outer casing having top, bottom and side walls, an inner casing located eccentrically of said top and bottom walls, a mechanically driven fan and an air driven fan in said inner casing and a spring for controlling said air driven fan, said two casings forming a passage for air currents therebetween, a revolution indicator mounted in the outer casing and means for operating the last indicator.

14. In a speedometer, an outer casing having top, bottom and side walls, an inner casing located eccentrically of said top and bottom walls, a mechanically driven fan and an air driven fan in said inner casing and a spring for controlling said air driven fan, said two casings forming a passage for air currents therebetween, a revolution indicator mounted in said outer casing and means for operating said last indicator, said means consisting of a worm on said mechanically driven fan.

In testimony whereof I have signed my name to this specification in the presence of two subscribing witnesses.

AUGUST J. KLONECK.
